UNITED STATES PATENT OFFICE.

ANGELO STEFANI, OF STARKVILLE, COLORADO; ROSIE STEFANI ADMINISTRATRIX OF
SAID ANGELO STEFANI, DECEASED.

FUEL AND WATER SUPPLY CAR.

Application filed September 6, 1924. Serial No. 736,318.

My present invention has reference to a coal and water system for traveling locomotives.

An object is to provide an elevated track disposed directly above the track on which a locomotive travels, an electrically operated car being provided for movement on the elevated track, and provided with a coal bin or receptacle as well as a water tank, the outlets of which being closed by separable valves, each operable by the motorman, and whereby the electrically propelled car may travel over and at the same rate of speed as the locomotive and deliver coal and water into the tender of the locomotive.

A further object is the novel arrangement of an overhead track for an electrically propelled car that carries a supply of water and coal to be delivered into the coal and water receptacles of the tender of a locomotive, and likewise to provide a means for replenishing the water and coal supply of the electrically driven car.

To the attainment of the foregoing broadly stated objects and others which will appear as the nature of the invention is better understood, reference is to be had to the drawings which accompany and which form part of this application.

In the drawings:—

Figure 1 is an elevation showing the manner in which a traveling locomotive is fed with water and coal in accordance with this invention.

Figure 2 is a side elevation showing the manner in which the coal and water supply for the electrically operated car is replenished.

Figure 3 is an enlarged side elevation of the electrically driven car or tender.

Figure 4 is a vertical transverse sectional view of the elevated track.

Figure 5 is a sectional view approximately on the line 5—5 of Figure 4.

The rails of an ordinary track for locomotives and the trains hitched thereto are indicated in the drawings by the numeral 1. A locomotive traveling on the said track is indicated by the numeral 2, the tender for the locomotive by the numeral 3. The tender is provided with the usual coal bin 4 and the water tank 5. In the present instance, the top of the bin 4 and the tank 5 are preferably open.

Along the sides of the rails providing the

track for the locomotive, I erect posts 6. These posts are connected by transverse beams 7 at their upper ends, suitable brace means 8 being provided between the posts and the connecting members 7.

On the inner face of each of the posts and disposed directly opposite each other there are secured angle brackets 9. The horizontal elements of these brackets have secured thereto the rails 10 of an elevated track. The right angular arms of the brackets are reinforced by webs. Secured to each of the posts 6, centrally of and above each of the brackets 9 there are the central portions 11 of angularly disposed arms 12. These arms are secured to the rails 10, and serve as additional braces therefor.

On the track provided by the rails 1 there is designed to travel an electrically propelled car 13. The car has fixed to the frame thereof and at the rear of the cab a coal bin 14 and a water tank 15, the latter being preferably tubular in cross section. The rear inclined wall 16 of the coal bin 14 provides the front wall for the tank 15 and the front wall of the bin is also arranged at a downward angle. This reduces the sides of the bottom of the bin and also positively directs the coal to the outlet opening thereof at the said bottom of the bin. The outlet opening is surrounded by a downwardly directed chute 17, the outlet whereof being controlled by a slide valve 18. Loosely connected to the outer end of the valve there is an arm 19 of an angle lever 20, the said lever being arranged in the car and being pivotally supported therein. A pull on the lever in one direction will throw the valve 18 to open position, and a push on the lever in an opposite direction will close the said valve. Of course, the chute 17 is suitably braced, one of the braces 21 connecting to the chute a pipe 22 communicating with two outlet pipes 23 and 24 that have their ends secured to the bottom of the tank 15. The pipe 22 has its passage controlled by a valve 25, the said valve having its stem operable by a rod 26 leading into and designed to be operated from the cab of the trolley car 13. The outlet pipe 22 has at its lower end an anti-splash funnel member 27.

Secured centrally on the transverse beams 7 for the posts 6 there is a trolley wire 28, the car 13 being provided with the usual trolley pole carrying wheel 29 for engagement with the trolley wire. This permits of the car 13

traveling in either direction over its elevated track.

As far as the description has progressed, it will be apparent that the trolley car 13 may be caused to travel at the same speed as the locomotive 2, so that the coal and water from the tender of the trolley car 13 may be delivered into the coal receptacle 4 and the water receptacle 5 in the tender 3 of the locomotive, 10 as illustrated in Figure 1 of the drawings.

In order that the electric tender may have its bin and tank replenished with coal and water, without necessitating the said car being moved off of its elevated track, I provide a 15 coal storage bin 30 arranged upon suitable vertical supports 31 directly above the top of the trolley car. The supply bin 3 has its bottom inclined to its center, the said center being provided with an outlet opening 20 rounded by a chute 31. The chute is controlled by a slideable door valve 32 operated by a handle 33. Suitable means 34 is provided for holding the pivoted handle 33 in a 25 position to sustain the door 32 in either its closed or open position. Also the door may be weighted so that the same will close automatically when the holding means 34 is released. Arranged centrally between the rails of the elevated track there is a vertical pipe 30 35 having a transversely swingable end 36 provided with a downwardly directed valve controlled nozzle 37. When the trolley car 13 is brought under the storage bin 30 the rear wheels thereof are blocked by elements 38 arranged on the rails 10 constituting the elevated track. This arranges the hopper 31 directly over the bin 14, and permits of the water pipe 35 having its end 36 swung to bring its nozzle 37 directly over the inlet for 40 the tank 17. The water inlet is arranged at the top of the tank 17 and is normally closed by a swingable cover valve 39. The valve for the nozzle 37 is then opened so that water can be directed through the pipe 35, into the tank 45 15.

It is, of course, necessary to supply the bin 30 with coal, and therefore there is supported directly above the said bin the straight ends of rails 40 that constitute the tracks for a 50 coal car 41. When arranged directly above the bin, the wheels of the car are brought against stop blocks 42 on the rails 40. What

I will term the forward end of the coal car 41 has secured thereto a cable 43 directed over suitable guide wheels 44 and connected to a 55 windlass (not shown), hitched to a source of power, also not shown. The rails 40 have one of their ends downwardly directed, as at 45, and these ends are suitably supported by means 46 (Figure 2). In this manner it will 60 be noted that the operation of the windlass will wind the cable 43 therearound and draw the car 41 up the rails of the inclined track 45 on to the straight rails 40 and properly position the car for dumping into the bin 30. 65 The car may be manually moved when the cable 43 is slackened to permit of the same gravitating on the inclined rails 45, the movement of the car in such direction being controlled by the slackening and the tightening 70 of the cable 43.

It is, of course, to be understood that the electricity for the trolley wire is supplied from a suitable nearby station.

It is believed that the foregoing description, when taken in connection with the drawings will fully set forth the construction and its advantages, but it is to be understood that I do not wish to be limited to the precise structural features herein set forth and may make 75 such changes therefrom as fairly fall within the scope of what I claim.

Having described the invention, I claim:

In a device for the purpose set forth, the combination, a wheeled frame designed to 80 travel upon an elevated track, a cab on one end of the frame, a coal bin directly to the rear of the cab and having its end walls inclined, a water tank formed on the rear end of the bin and divided therefrom by the rear wall of 90 said bin, a depending chute at the reduced bottom of the coal bin, a slideable valve for controlling the passage through the chute, lever operated means in the cab for actuating the valve, pipes leading from the bottom and 95 disposed adjacent to the front and rear of the water tank, and said pipes being connected and having a common outlet, a valve controlling the passage through the outlet, an operating rod for the valve leading into the cab, and brace means between said pipe and said chute.

In testimony whereof I affix my signature.

ANGELO STEFANI.
